APPARATUS FOR STIMULATING BLOOD CIRCULATION

John H. Emerson, Cambridge, Mass.

Application June 13, 1935, Serial No. 26,420

10 Claims. (Cl. 128—299)

My invention relates to apparatus for stimulating blood circulation in localized portions of the human body, for relief of arteriosclerosis, embolic occlusion and similar afflictions where 5 the blood circulation has become retarded or even entirely stopped in a portion of the body.

This invention utilizes the broad principle of placing the portion of the body to be treated in an air-tight enclosure and then causing alternate negative and positive or atmospheric pressures to be created within the enclosure and upon the surface of the enclosed portion of the body.

Since such an apparatus may be used for treating different diseases and varying degrees of 15 blood circulation afflictions, and since different doctors frequently desire different pressure conditions, different durations of each cycle of positive and negative or atmospheric pressures and different ratios of negative pressure time to positive pressure time or atmospheric pressure time in each cycle for the treatment of the same affliction it is of great importance and utility to provide adjustable means for controlling these 20 conditions.

25 In use the effect which the apparatus is having upon the member being treated can best be determined by observing the variations of surface color of the member and it is therefore important to provide an enclosure for the member which is both transparent and non-shatterable, the former 30 quality allowing inspection of the member during treatment and the latter quality providing an enclosure which will not only withstand the pressures necessarily exerted upon the interior of the enclosure by the apparatus, but will also withstand accidental exterior shocks or forces the 35 breaking effect of which upon the enclosure is greatly increased when in use because of the negative pressures upon the interior thereof.

40 For example, glass has been found unsatisfactory for the manufacture of such an enclosure due to its shatterable qualities and the resultant danger of cutting the patient's body in the event of breakage.

45 The principal object of this invention is to provide a novel apparatus for stimulating blood circulation in portions of the human body.

Further objects are to provide an apparatus 50 of this character with adjustable means for controlling the intensities of both negative and positive pressure; with adjustable means for controlling the duration of each cycle of negative and positive pressures and with adjustable means 55 for increasing or decreasing the ratio of each

period of negative pressure to each period of positive pressure in each cycle.

Another object is to provide an apparatus of this character which will produce alternate negative and atmospheric pressures upon the portion 5 of the body being treated, and which is provided with adjustable means for controlling the intensities of negative pressure; with adjustable means for controlling the duration of each cycle of negative and atmospheric pressures and with 10 adjustable means for increasing or decreasing the ratio of each period of negative pressure to each period of atmospheric pressure in each cycle.

A further object is to provide a novel means 15 for enclosing the portion of the body to be treated.

Further objects are to provide enclosing means which is both transparent and non-shatterable and to provide enclosing means for the leg and 20 foot capable of receiving any size leg and foot.

A further object is to provide novel means for sealing between the enclosing means and the patient's body. Another object is to provide means for adjusting the size of the sealing 25 means.

Other objects relate to the construction and mode of operation and will be apparent from consideration of the following description and accompanying drawings which exemplify one embodiment of my invention chosen for the purposes of illustration.

In the drawings:—

Fig. 1 is a view in side elevation of a casing 35 for enclosing the leg of a patient, with a sealing member in place on one end thereof;

Fig. 2 is an end view of the casing shown in Fig. 1, with sealing member removed;

Fig. 3 is an end view of a sealing member having two telescoping inserts for reducing the inside 40 circumference thereof;

Fig. 4 is a view in perspective of the sealing member and inserts shown in Fig. 3;

Fig. 5 is a view in side elevation, with parts broken away, of an apparatus for producing alternate variations of pressure;

Fig. 6 is a plan view of the apparatus shown in Fig. 5;

Fig. 7 is a view in side elevation of the lower part of the apparatus shown in Fig. 5, taken 50 from the reverse side thereof;

Fig. 8 is an enlarged view in side elevation, with parts broken away and shown in section, of the valves for placing sources of different pressures alternately in communication with the cas- 55

ing and of valves for regulating the intensities of positive and negative pressures thus placed in communication with the casing;

Fig. 9 is an enlarged section on the line 9—9 of Fig. 8;

Fig. 10 is an enlarged section on the line 10—10 of Fig. 8;

Fig. 11 is an enlarged plan view of the mechanism for varying the duration of each cycle of negative and positive or atmospheric pressures and for alternately opening and closing communications between sources of such pressures and the casing; and

Fig. 12 is a view in cross section, with parts broken away, of a sealing member and two telescoping inserts of modified form.

Referring to Figs. 1 and 2, the means for enclosing the portion of the patient's arm or leg and foot comprises a hollow casing 10 made of a strong, non-shatterable, transparent material, such as cellulose acetate. This casing has one end which is open and one end which is closed by an end piece 11. The casing is of substantially elliptical cross section and its side wall tapers inwardly from the closed end to the open end. The arcuate side wall of the casing is made of two flat sheets of cellulose acetate (see Fig. 2), each of which is bent or bowed outwardly so that their longitudinal edges overlap. The portion of overlap is sealed and partially secured by a coating of any suitable cement and the side wall sheets are retained in outwardly bowed shape by means of metallic reinforcing bands 12 which extend transversely around the outside of said sheets in contact with the outer surfaces thereof.

A standard 13 is secured to the casing adjacent its closed end to support and steady it when used in horizontal or inclined position. A pipe or conduit 14 provides a communication between the interior of the casing 10 and a pressure controlling mechanism hereinafter more fully described. A gauge 15 communicates with the interior of the casing and indicates the variations of pressure therein above and below atmospheric pressure.

The open end of the casing is of sufficient size to admit a very large sized human foot with the ankle properly flexed, and the closed end of the casing is of sufficient size to accommodate such a foot when extended at right angles to the patient's leg.

A casing so constructed can also be used with smaller feet and shorter legs, and although with a shorter leg, the foot will be located at some distance from the closed end of the casing, the walls are tapered so as to accommodate different decreasing sizes of feet, as shown by the dot dash leg and foot in Fig. 1. This casing may also be used for the treatment of arms and hands.

A tubular rubber collar 16, preferably made of sponge rubber and having a flexible impervious rubber coating or skin 93 on the outside, is provided to seal the space between the open end of the casing and the adjacent portion of the patient's leg or arm. In use one end of the collar snugly encircles the leg or the arm of the patient and the other end of the collar snugly encircles the outer wall at the open end of the casing, as shown in Fig. 1.

A tubular reinforcing member 97 made of non-expansive material such as a woven fabric impregnated with rubber is provided to surround the portion of the rubber collar which encircles the patient's leg or arm. This reinforcing member ensures an air-tight seal between the patient's

leg or arm and the rubber collar since it prevents expansion of the periphery of the collar even when high positive pressures are exerted within the casing. The reinforcing member may be physically attached to the outside of the rubber collar or it may be a separate piece, and slipped over the collar.

A tubular rubber insert 17, also preferably of sponge rubber, is of such a size that its outer circumference snugly fits within the inner circumference of the tubular collar 16, as shown in Figs. 3 and 4. This insert may be considerably shorter than the collar and in use it encircles the patient's leg or arm and does not encircle the open end of the casing. The insert is thus used to supplement the rubber collar 16 in the treatment of legs or arms too small to be sealed by the larger diameter of the rubber collar.

If desired, additional inserts 18 may be provided to accommodate still smaller legs or arms.

The modified type of insert 90 illustrated in Fig. 12 is provided with a bead or flange 91 on its outer end. This flange contacts the outer end of the collar 16 and prevents the insert from sliding through the collar when the leg or arm of the patient is inserted therein. Additional inserts 92 are also provided with flanges which contact the respective adjacent outer ends of the adjacent inserts.

When the casing 10 and the rubber collar 16 are in place upon the portion of the body to be treated they provide an air-tight chamber surrounding said portion.

The apparatus for producing alternate pressure variations is mounted in a cabinet 19 (Fig. 5) which is provided with rollers or casters so that it may be easily moved from place to place. Upon a suitable support in the lower compartment of the cabinet is mounted a motor 20 which is connected to an electric cable 21 which may be plugged into a source of electric current, such as a wall socket. A rotary compressor 22 is likewise mounted in the lower part of the cabinet and is capable of producing a constant source of both positive and negative pressures of substantially constant intensities, the compressor being driven by the motor 20 by means of a belt 26.

The positive pressure is conducted from the compressor by a conduit or pipe 23 provided with a suitable filter 24 and the negative pressure is conducted from the compressor by means of a conduit or pipe 25.

A valve casing 27 (Figs. 5 and 8) is supported by a fixture 28 in the upper portion of the cabinet. The valve casing 27 has four axial chambers 29 each of which has three ports, the first port, a positive pressure port 30 at the upper end communicating with the positive pressure conduit 23 by means of the passage 31 in the fixture 28; the second port 32, a negative pressure port, at the lower end communicating by means of the conduit 33 with the negative pressure conduit 25; and the third port 34, intermediate the first two ports and communicating with the conduit 14 leading to the casing 10.

A positive pressure valve 35, located adjacent the outside of the positive pressure ports 30, is adapted to open and close said ports 30. A spring 36 bears against the outside of said positive pressure valve 35 and exerts pressure against it normally tending to hold it in closed position with respect to said positive pressure ports.

A negative pressure valve 37 located adjacent to the outside of the negative pressure ports 32 is adapted to open and close said ports. The 75

valves 35 and 37 are secured to valve stems 38 which are slidably mounted in suitable guides, the inner ends of the valve stems being maintained in abutting relation. These stems 38 are made of such lengths that when their ends abut the valves are held further apart than the distance between the valve seats and consequently both valves can not be closed at the same time.

The spring 36 normally holds the positive pressure valve 35 closed and the negative pressure valve 37 open. When the valves are in such positions the casing 10 is in communication with the constant negative pressure created by the compressor. Such communication is provided by the conduit 14, the dust filter 39, the ports 34, the valve chambers 29, the ports 32, the conduit 33, the safety valve 83 and the conduit 25.

The negative pressure valve 37 is closed and the positive pressure valve 35 is opened by exerting force upwardly against the negative valve 37 through the stem 38 to the positive pressure valve 35 and thence against the lower end of the spring 36, thereby moving said valves upwardly with respect to the chambers 29, and thereby also compressing the spring 36. As soon as this upward force is released the spring 36 immediately returns the valves to their normal position in which the valve 37 is open and the valve 35 closed.

When sufficient upward force is exerted to close the valve 31 the casing 10 is in communication with the constant positive pressure of the compressor by means of the conduit 14, the valve chambers 29, the positive pressure ports 30, the passage 31 and the conduit 23.

The upward force for closing the negative valves and compressing the spring 36 is created by rotating a crank 49 (Figs. 5 and 7). The free end of this crank is pivotally connected by a pivot pin 51 to the lower end of a connecting rod 41, and the upper end of said rod is connected to the lower end of a spring 42. The upper end of the spring 42 is connected to the lower end of another connecting rod 43 and the upper end of this connecting rod is threaded and passes freely through an aperture in one end of the lever 44. An adjusting nut 45 is screwed upon the protruding threaded end of the rod 43.

The other end of the lever 44 engages the lower end of a rod 46 (Fig. 8) and the upper end of the rod 46 engages the outer end of the lower valve stem 38. A sylphon 47 provides a flexible air-tight seal between the rod 46 and the negative pressure chamber 48.

A bracket 49 attached to the fixture 28 is provided at its lower end with a slot to receive the lever 44 and the lever is pivotally supported in the slot by means of a fulcrum pin 50 extending transversely through the lever and the sides of said slot in the bracket 49 thereby forming a fulcrum about which the lever may rotate for a short distance in a vertical plane.

The nut 45 is adjusted so that the sum of the operative length of the connecting rod 43, the length of the contracted spring 42 and the operative length of the connecting rod 41 will equal the distance between the lower surface of the nut 45 and the connecting pin 51 when the crank is in horizontal position, the positive valve 35 closed, the inner ends of the valve stems 38 abutting and the lower end of the rod 46 abutting the upper adjacent surface of the lever 44 as shown in Figs. 5 and 8. Thus when the crank is in horizontal position such as at the three or nine o'clock positions looking at Fig. 7, no tension will be created

in the connecting rods 41 and 43 or in the spring 42, but as the crank rotates in a clockwise direction from three to nine o'clock, tension will be created in said rods and spring during said interval of rotation, and the lever 44 will be moved slightly in a vertical plane about its fulcrum 50 and will cause an upward force to be exerted on the rod 46, thereby closing the negative pressure valve 37, opening the positive pressure valve 35 and compressing the spring 36. During this portion of the crank's rotation, the coil spring 42 will be gradually extended as the crank moves from three to six o'clock and gradually collapsed as it moves from six to nine o'clock. As soon as the crank reaches the nine o'clock position the spring 42 is completely collapsed and the tension in the rods 41 and 43 is released and remains released while the crank travels from nine to three o'clock position. Thus at nine o'clock upward force in the rod 46 is released and the spring 36 closes the positive pressure valve 35 and opens the negative pressure valve 37 and these valves will remain in such positions until the crank again reaches three o'clock position and again creates tension in the connecting rods 41 and 43.

One complete revolution of the crank will thus cause a complete cycle of positive and negative pressures within the casing and if, for example, the crank makes one revolution in twenty seconds there will be ten seconds of negative pressure and ten seconds of positive pressure created in the casing 10. If, for example, fifteen seconds of negative and five seconds of positive pressure is desired during each twenty-second cycle the nut 45 is unscrewed far enough to increase the operative length of the rod 43 so that tension will be created in the connecting rods 43 and 41 and in the spring 42 during only one-fourth of each revolution of the crank thereby causing the positive pressure valve to be held open only one-fourth of the revolution, namely five seconds, and the negative pressure valve to be held open during the other three-fourths of the revolution, namely fifteen seconds. By adjusting the nut 45 any ratio of duration of positive pressure to duration of negative pressure during each cycle may be obtained.

The crank is journaled in transverse holes in the parallel spaced standards 53 and secured to a gear 52 located between said standards so that both crank and gear rotate together at the same speed. A friction wheel 54 is mounted for rotation between the standards 53 and above the gear 52. A gear 55 is mounted for rotation between the standards 53 intermediate the friction wheel 54 and the gear 52 and is adapted to mesh with suitable gears thereon and thereby to transmit the rotary motion of the wheel to the gear 52 and to the crank attached thereto, as illustrated. The standards 53 are pivotally mounted on a horizontal rod 56 which passes through holes near the lower extremities of said standards. The horizontal rod 56 is supported by the vertical rod 57 to which one of its ends is firmly attached. The vertical rod 57 is provided near its lower end with a horizontal shoulder 58 which bears upon a plate 59 and this plate is attached to a frame member of the cabinet by the screw 60. The upper end of the vertical rod 57 extends loosely through a hole in the floor of the upper portion of the cabinet 70 and a horizontal handle 61 is firmly attached to the upper end of the vertical rod.

The plate 59 is provided with two upstanding stops 63 which are high enough to contact the free end of the horizontal rod 56 to confine rota-

tion of the vertical rod 57 to the angle formed by lines drawn from the stops to the vertical rod as shown in the dot and dash positions of the horizontal rod 56 in Fig. 11.

5 A horizontal projecting member 62 has one end firmly attached to the vertical rod 57 near its lower extremity. A spring 64 has one end bearing against the horizontal projecting member 62 and the other end bearing against a cross piece 65

10 which is firmly attached between the standards 53 by means of screws 66a. This spring tends to exert force against the left-hand edge of said cross piece 65 (looking at Figs. 7 and 11) and thus tends to rotate the standard 53 clockwise in a

15 vertical plane about the horizontal rod 56. Said cross piece 65 also acts as a spacing member to hold the standards 53 in parallel spaced relationship.

The circumference of the friction wheel 54 is 20 provided with a friction surface, for example, a rough rubber tire 66 and this friction surface contacts a conical shaft 67. The spring 64 tends to hold this friction surface in constant contact with the shaft 67 by the force which it exerts 25 against the edge of the cross piece 65.

The motor 20 rotates the conical shaft 67 at a constant speed, and the shaft in turn rotates the wheel 54, which by means of the gears 55 and 52, rotates the crank 40 at a constant speed.

20 The speed of rotation of the crank 40 can be varied by rotating the handle 61 in a horizontal plane since such movement of the handle rotates the vertical rod 57 and the friction wheel 54 in horizontal planes. As the friction wheel 54 is 25 rotated horizontally in a clockwise direction, looking at Fig. 11, its surface contacts a smaller circumference of the conical shaft 67 and consequently the speeds of the wheel 54 and the crank 40 are correspondingly reduced. Thus by moving

30 the handle 61 the time taken for each cycle of the crank 40 may be varied and controlled and consequently the time of each cycle of positive and negative pressures is correspondingly varied or controlled.

35 45 A slotted member 70 is provided to retain the handle 61 in any desired position (Fig. 6).

A positive pressure safety valve 71 is provided above the ports 72, which ports communicate with the upper ends of four axial chambers 73 in

50 the valve casing 74. A chamber 75 above the valve 71 communicates with atmospheric pressure through the port 76. The valve is mounted on the fixture 28 above passage 31 in said fixture and the lower ends of the axial chambers 73 communicate with the passage 31 which in turn communicates with the positive pressure line 23 by

55 means of the protruding pipe conduit 77. One end of the spring 78 bears against the top of the valve 71 and the other end bears against the lower surface of a shoulder 79. The shoulder 79 is attached to the lower end of the stem of the thumb screw 80 which is mounted for turning movement in the upper end of the valve casing 74. Suitable air-tight packing 81 is provided between

60 65 the valve casing and the stem of the thumb screw.

The spring 78 normally tends to hold the valve 71 in closed position with respect to the port 72. When the positive pressure in the chamber 31

70 reaches a great enough intensity to force the valve 71 upwardly and to thus compress the spring 78, the chamber 31 will be connected with atmospheric pressure through the axial chambers 73, the chamber 75 and the port 76 and the intensity of positive pressure in the chamber 31 will

be diminished by this source of atmospheric pressure until the force in the spring 78 forces the valve 71 closed again. By tightening or loosening the thumb screw 80 the force exerted by the spring 78 against the valve 71 is increased or decreased and the force resisting opening of the valves by positive pressure in the chamber 31 is correspondingly increased or decreased. Since the valve casing 74 is located on the positive pressure line between the source of positive pressure 10 and the casing 10, it affords adjustable means for controlling the intensities of positive pressures which may pass through the positive pressure line to the casing 10.

A negative pressure safety valve 82 is provided in a valve casing 83 which is mounted upon the fixture 28. This casing, like the positive pressure safety valve, is provided with four axial chambers, but the lower ends of these axial chambers communicate with atmospheric 20 pressure through a port 84. A threaded thumb screw is mounted in the top of the valve casing 83, and the lower end of the thumb screw stem is provided with a shoulder which abuts the upper end of a spring. The lower end of the spring 25 bears against the upper surface of the valve 82 and tends to hold it in closed relation with respect to the ports in the upper ends of the axial chambers 73. The conduit 25 from the negative pressure side of the compressor is connected by means of the port 85 with a chamber 30 in the valve casing located above the valve 82, and this chamber is connected with the negative pressure side of the alternating valve 37 through the port 86 and the conduit 33.

35 When the negative pressure in the conduit 25 reaches a great enough intensity the valve 82 is sucked upwardly and opens communication with atmospheric pressure through the chambers 73 and the port 84. When the atmospheric pressure 40 has sufficiently reduced the intensity of the negative pressure the spring will close the valve 82. By tightening or loosening the thumb screw, the force exerted by the spring against the top of the valve 82 is increased or decreased and the maximum intensity of negative pressure in the conduit 33 is correspondingly increased or decreased. This device thus affords adjustable means for controlling the intensities of negative pressure which may pass from the compressor to the 50 casing 10.

45 Alternate negative and atmospheric pressures may be obtained in the casing by removing the conduit 23 from the protruding pipe 77. The valve 35 then communicates with atmospheric 55 rather than positive pressure.

In practice the following conditions are frequently prescribed: cycles varying from ten to sixty seconds; from one-half to four-fifths of each cycle negative pressure and from one-fifth to one-half the cycle either positive or atmospheric pressure; negative pressures up to twelve centimeters of mercury and positive pressures up to ten centimeters of mercury. I do not propose to prescribe any of the above conditions for the treatment of any disease or affliction. I give them merely as rough estimates for air in designing a compressor, motor, safety valves and alternating mechanism for an apparatus of this character.

70 In operation the handle 61 is adjusted to give the desired duration of each cycle of alternate pressures, the nut 45 is adjusted to provide the desired duration of negative pressure and the desired duration of positive pressure during each 75

cycle, and the thumb screws on the positive and negative safety valves are adjusted to provide the respective desired intensities of positive and negative pressures. The leg or arm of the patient is then inserted through the opening in the rubber collar, one end of which is in place around the open end of the casing. The power is then switched on, actuating the motor, the compressor and the alternator. The operator 10 may then observe the gauge 15 to check the conditions within the casing, and during treatment he may observe both the gauge 15 and the member being treated, and if variations of the aforesaid conditions are desired during treatment they can be made without stopping the motor by adjusting the handle 64, the nut 45 or the safety valve thumb screws.

If operation to provide alternate negative and atmospheric pressures is desired, the conduit 23 20 is disconnected from the projecting pipe 17 and the procedure is then the same as with alternate positive and negative pressures, excepting that no adjustment of the positive pressure safety valve is required.

25 I claim:

1. An apparatus for stimulating blood circulation comprising a hollow casing for receiving a portion of the patient's body, means for forming an air-tight seal between the casing and the patient's body, a chamber communicating with said casing, said chamber having a port communicating with a source of positive pressure and another port communicating with a source of negative pressure, a valve associated with said positive pressure port, a valve associated with said negative pressure port, resilient means associated with one of said valves normally holding one valve in closed position and the other valve in open position with respect to their respective ports and means for periodically compressing said resilient means, comprising a lever pivotally mounted on a fulcrum intermediate its ends, one end of said lever associated with said resilient means and adapted to compress the same, the other end of said lever connected to one end of a connecting member, the other end of said connecting member connected to the free end of a crank, and means to rotate the crank in a complete cycle, said connecting member being of such an operative length that tension is created therein during only part of each cycle of the crank, thereby causing the lever to move about the fulcrum and to compress said resilient means during only part of each cycle of the crank.

55 2. An apparatus for stimulating blood circulation comprising a hollow casing for receiving a portion of the patient's body, means for forming an air-tight seal between the casing and the patient's body, a chamber communicating with said casing, said chamber having a port communicating with atmospheric pressure and another port communicating with a source of negative pressure, a valve associated with said atmospheric pressure port, a valve associated with said negative pressure port, resilient means associated with one of said valves normally holding one valve in closed position and the other valve in open position with respect to their respective ports and means for periodically compressing said resilient means, comprising a lever pivotally mounted on a fulcrum intermediate its ends, one end of said lever associated with said resilient means and adapted to compress the same, the other end of said lever connected to one end of a connecting member, the other end of said connecting member connected to the free end of a crank, and means to rotate the crank in a complete cycle, said connecting member being of such an operative length that tension is created therein during only part of each cycle of the crank, thereby causing the lever to move about the fulcrum and to compress said resilient means during only part of each cycle of the crank.

to one end of a connecting member, the other end of said connecting member connected to the free end of a crank and means to rotate the crank in a complete cycle, said connecting member being of such an operative length that tension is created therein during only part of each cycle of the crank, thereby causing the lever to move about the fulcrum and to compress said resilient means during part of each cycle of the crank.

3. An apparatus for stimulating blood circulation comprising a hollow casing for receiving a portion of the patient's body, means for forming an air-tight seal between the casing and the patient's body, a chamber communicating with said casing, said chamber having a port communicating with a source of positive pressure and another port communicating with a source of negative pressure, a valve associated with said positive pressure port, a valve associated with said negative pressure port, resilient means associated with one of said valves normally holding one valve in closed position and the other valve in open position with respect to their respective ports and means for periodically compressing said resilient means comprising a lever pivotally mounted on a fulcrum intermediate its ends, one end of said lever associated with said resilient means and adapted to compress the same, the other end of said lever connected to one end of a connecting member, the other end of said connecting member connected to the free end of a crank, and means to rotate the crank in a complete cycle, and means on said connecting member to vary the operative length thereof thereby varying the portion of the cycle of the crank during which tension is created in the connecting member.

4. An apparatus for stimulating blood circulation comprising a hollow casing for receiving a portion of the patient's body, means for forming an air-tight seal between the casing and the patient's body, a chamber communicating with said casing, said chamber having a port communicating with atmospheric pressure and another port communicating with a source of negative pressure, a valve associated with said atmospheric pressure port, a valve associated with said negative pressure port, resilient means associated with one of said valves normally holding one valve in closed position and the other valve in open position with respect to their respective ports and means for periodically compressing said resilient means, comprising a lever mounted on a fulcrum intermediate its ends, one end of said lever associated with said resilient means and adapted to compress the same, the other end of said lever connected to one end of a connecting member, the other end of said connecting member connected to the free end of a crank, and means to rotate the crank in a complete cycle, said connecting member being of such an operative length that tension is created therein during only part of each cycle of the crank, thereby causing the lever to move about the fulcrum and to compress said resilient means during only part of each cycle of the crank.

5. An apparatus for stimulating blood circulation comprising a hollow casing for receiving a portion of the patient's body, means for forming an air-tight seal between the casing and the patient's body, a chamber communicating with said casing, said chamber having a port communicating with a source of positive pressure and another port communicating with a source of negative pressure, a valve associated with said positive pressure port, a valve associated with said negative pressure port, resilient means as-

5 associated with one of said valves normally holding one valve in closed position and the other valve in open position with respect to their respective ports and means for periodically extending said resilient means, said means for extending comprising a lever pivotally mounted on a fulcrum intermediate its ends, one end of said lever associated with said resilient means and adapted to extend the same, the other end of said lever connected to one end of a connecting member, the other end of said connecting member connected to the free end of a crank, and means to rotate the crank in a complete cycle, said connecting member being of such an operative length that tension is created therein during only part of each cycle of the crank, thereby causing the lever to move about the fulcrum and to extend said resilient means during only part of each cycle of the crank.

10 6. An apparatus for stimulating blood circulation comprising a hollow casing for receiving a portion of the patient's body, means for forming an air-tight seal between the casing and the patient's body, a chamber communicating with said casing, said chamber having a port communicating with atmospheric pressure and another port communicating with a source of negative pressure, a valve associated with said atmospheric pressure port, a valve associated with said negative pressure port, resilient means associated with one of said valves normally holding one valve in closed position and the other valve in open position with respect to their respective ports and means for periodically extending said resilient means, said means for extending comprising a lever pivotally mounted on a fulcrum intermediate its ends, one end of said lever associated with said resilient means and adapted to extend the same, the other end of said lever connected to one end of a connecting member, the other end of said connecting member connected to the free end of a crank and means to rotate the crank in a complete cycle, said connecting member being of such an operative length that tension is created therein during only part of each cycle of the crank, thereby causing the lever to move about said fulcrum and to extend said resilient means during part of each cycle of the crank.

15 7. An apparatus for stimulating blood circulation comprising a hollow casing for receiving a portion of the patient's body, means for forming an air-tight seal between the casing and the patient's body, a chamber communicating with said casing, said chamber having a port communicating with a source of positive pressure and another port communicating with a source of negative pressure, a valve associated with said positive pressure port, a valve associated with said negative pressure port, resilient means associated with one of said valves normally holding one valve in closed position and the other valve in open position with respect to their respective ports and means for periodically extending said resilient means, said means for extending comprising a lever pivotally mounted on a fulcrum intermediate its ends, one end of said lever associated with said resilient means and adapted to extend the same, the other end of said lever connected to one end of a connecting member, the other end of said connecting member connected to the free end of a crank, means to rotate the crank in a complete cycle, and means on said connecting member to vary the operative length thereof thereby varying the por-

tion of the cycle of the crank during which tension is created in the connecting member.

8. An apparatus for stimulating blood circulation comprising a hollow casing for receiving a portion of the patient's body, means for forming an air-tight seal between the casing and the patient's body, a chamber communicating with said casing, said chamber having a port communicating with atmospheric pressure and another port communicating with a source of negative pressure, a valve associated with said atmospheric pressure port, a valve associated with said negative pressure port, resilient means associated with one of said valves normally holding one valve in closed position and the other valve in open position with respect to their respective ports and means for periodically extending said resilient means, said means for extending comprising a lever mounted on a fulcrum intermediate its ends, one end of said lever associated with said resilient means and adapted to extend the same, the other end of said lever connected to one end of a connecting member, the other end of said connecting member connected to the free end of a crank, means to rotate the crank in a complete cycle and means on said connecting member to vary the operative length thereof thereby varying the portion of the cycle of the crank during which tension is created in the connecting member.

9. An apparatus for stimulating blood circulation comprising a hollow casing for receiving a portion of the patient's body, means for forming an air-tight seal between the casing and the patient's body, a chamber communicating with said casing, said chamber having a port communicating with a source of positive pressure and another port communicating with a source of negative pressure, a valve associated with said positive pressure port, a valve associated with said negative pressure port, resilient means associated with said valves normally holding one valve in closed position and the other valve in open position with respect to their respective ports, and means for periodically extending said resilient means, said means for extending comprising a lever mounted for movement about a fulcrum, a connection between said lever and said resilient means, and means for periodically actuating said lever about said fulcrum to extend said resilient means from its normal position. 30 35 40 45 50

10. An apparatus for stimulating blood circulation comprising a hollow casing for receiving a portion of the patient's body, means for forming an air-tight seal between the casing and the patient's body, a chamber communicating with said casing, said chamber having a port communicating with a source of positive pressure and another port communicating with a source of negative pressure, a valve associated with said positive pressure port, a valve associated with said negative pressure port, resilient means associated with said valves normally holding one valve in closed position and the other valve in open position with respect to their respective ports, and means for periodically compressing said resilient means, said means for compressing comprising a lever mounted for movement about a fulcrum, a connection between said lever and said resilient means, and means for periodically actuating said lever about said fulcrum to compress said resilient means from its normal position.
